UNITED STATES PATENT OFFICE

IGNATZ SALZ, OF NEW YORK, N. Y.

SPECIAL TOOL

Application filed October 5, 1929. Serial No. 397,707.

This invention relates to special tools, and the improvements are directed to a novel form of device for setting the feeder and pen within the nozzle portion of a fountain pen.

As will presently appear it is proposed to provide a fixed member and a movable member adapted to receive a feeder and pen and to maintain the articles in a definite or pre-determined position during the attachment of the usual nozzle portion of the fountain pen thereto.

The invention is featured by the introduction of novel means, associated with said fixed member, whereby the pen and feeder are arranged and maintained in proper assembled relation prior to the operation of the movable member and the affixing of the nozzle to said pen and feeder.

Another object of the invention is to provide a novel abutment or guard member, which normally embraces said feeder and pen and which is susceptible of adjustment to limit the extent of the insertion of the nozzle over said feeder and pen.

Still another object is to provide means whereby said movable member is operated relatively to said fixed member, said means being adjustable to command the movement of said movable member.

A still further object of the invention resides in the provision of a tool of the above-mentioned character, which is adapted to accommodate the varying sizes of pens and feeders, and which materially increases the output of the articles with greater precision heretofore attained by usual manual operations.

With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

Figure 1 is a front elevation of the tool, partly in section, showing the attachment of the fixed member to a suitable support, such

as the top of a bench, or the like, and also illustrating foot-operable mechanism normally positioned beneath the support.

Fig. 2 is a transverse sectional view taken on the line 2—2 of Fig. 1.

Fig. 3 is a plan view of the upper or movable member and depicting the means for adjusting the abutment or guard members.

Fig. 4 is a plan view of the lower, or fixed member, removed from its companion parts, and illustrating a pen, feeder and nozzle assembled therewith.

Fig. 5 is an elevation of the front edge of the movable member.

Fig. 6 is a sectional view like unto Fig. 2, but showing the feeder and pen in position pending the operation of said movable member.

Fig. 7 is also similar to Fig. 2, but showing the movable member in lowered or clamping position, and further illustrating the function of the abutment or guard member insofar as the nozzle is concerned.

Referring now more in detail to the accompanying drawings, wherein like characters of reference denote similar parts throughout the several views, let 10 indicate the fixed member, which is provided with countersunk bores 11, (see Fig. 4) for the reception of bolts 12, whereby said member is secured to a support 13. It will be noted upon inspection of Fig. 1 that said support 13 is provided with an opening 14, to permit the reciprocation of certain parts, as will presently appear.

The movable member 15 is maintained at an elevated position above said fixed member 10 through the intermediary of a vertical rod 16, the latter being preferably threaded at its upper end for threaded engagement with the threaded opening 17 in said movable member. The lower end of said rod 16 is normally partially inserted in a dashpot arrangement 18, the lower face of said rod abutting a spring 19, the latter exerting an upward vertical thrust on said rod, as is quite obvious. In view of the flanged collar 20, which is slidably adjustable on said rod 16, by means of the setscrew 21, the degree of elevation of said movable member

with respect to said fixed member, may be regulated as desired.

The mechanism for operating said movable member 15 comprises a foot-operable lever 22, pivotally connected to said rod 16, as indicated at 23, one of its ends being hingedly coupled to a bracket 24, as indicated at 25, said bracket being supported by a plate 26, also carrying said dash-pot 18. From the foregoing it is obvious that when pressure is applied to the end portion 22a of said lever 22, the rod 16 and movable member 15 descend in unison thus tensioning the spring 19. When the pressure is removed the spring rebounds and moves said rod upwardly until said flanged collar 20 abuts the lower face of said fixed member 10.

Reverting now to said fixed member 10, with special reference to Fig. 4, it will be noted that the same is provided with a plurality of vertical pins 27, which protrude above the top face of said member for insertion in apertures 28 in said movable member 15, (see Fig. 3), said pins 27 and apertures 28 cooperating to assure a true vertical reciprocation of said movable member during the operation of the device. As shown in Fig. 4 said fixed member 10 is provided with a plurality of recesses 29 of varying dimensions to accommodate the different sizes of feeders, each recess being associated with a pair of pins 30, which latter are notched as indicated at 31, (see Figs. 1 and 2). The front edge of said member 10 is provided with a series of grooves 32 and also a central opening 33 within which said rod 16 reciprocates.

As clearly shown in Figs. 4 and 6, the feeder 34 may be placed within a suitable recess 29, whereupon a pen 35 is mounted upon said feeder and moved forwardly thereon until the edges of the nib portion engaged within the notches 31 of said pins 30; the relative positions of said pins, notches and recesses being predetermined so that the position of said feeder and pen mentioned above is the correct assemblage. With the parts arranged as aforesaid, the movable member 15 is lowered by manipulating said lever 22 until said member abuts the upper surface of the pen, as shown in Fig. 7. Said feeder and pen being thus clamped together, the nozzle 36 may be inserted thereover.

The mechanism thus far described assures the correct assembling of the feeder and pen which is extremely important. However, it is equally essential that the nozzle be inserted over said feeder and pen a sufficient and definite distance in order that efficient operation of the parts may be assured. To this end, it is proposed to provide abutment or guard members, which will now be described.

Upon inspection of Figs. 3 and 5, it will be

observed that the top face of said movable member 15 is transversely grooved, as indicated at 37, said groove continuing through the front edge of said member as indicated at 38, thus providing continuous grooves adapted to receive the L-shaped guard members 39. The shorter leg of said members 39 are each provided with an elongated slot 40, through which the feeder is inserted to a selected recess 29. The lower end of the shorter legs of said members 39 slides in grooves 32 during the reciprocation of the movable member, when said members 39 are assembled with said movable member as shown in Fig. 7. In view of the slots 41 and set-screws 42, (see Fig. 3), it is possible to advance the shorter legs of said members 39, and thus the extent of the insertion of a nozzle member over the feeder and pen may be regulated as desired. In Figs. 6 and 7 the guard member 39, that is, the shorter leg thereof, is within the grooves 38—32 and hence said nozzle may be inserted until it abuts the face of said member. In the event the shorter leg is advanced to the left of that shown in Figs. 6 and 7, the extent of the insertion of said nozzle member over the feeder and pen, is restricted accordingly.

In view of the variance in the size of the recesses 29, different sized pens and feeders may be accommodated, and as the clamping action exerted on both feeder and pen is positive, the insertion of the nozzle as aforesaid may be affected without disturbing the proper relation between said pen and feeder. In short, the grooves 29 properly position the feeders, the pins 30 and notches 31 accurately position the pens with relation to said feeders and finally the adjustability 105 of the guard members limits the degree of insertion of said nozzles after the movable member 15 has been lowered to its clamping position as aforesaid.

As shown in Fig. 2, the lower face of said movable member may be recessed, as indicated at 43, to receive a portion of the pins 30 when the movable member descends.

Various slight changes might be made in the general form and arrangement of the parts described without departing from the invention and hence I do not limit myself to the precise details set forth, but consider myself at liberty to make such changes and alterations as fairly fall within the spirit and scope of the appended claims.

I claim:

1. A tool of the class described including a fixed member having a groove adapted to receive a feeder of a fountain pen, a pair of pins carried by said member and adapted to limit the position of a pen with respect to said feeder, a member adapted to be reciprocated over said fixed member and means associated with the last-named mem- 120 125 130

ber whereby the extent of the insertion of a nozzle over said feeder and pen may be regulated.

2. A tool of the class described including a fixed member having a plurality of grooves into a selected one of which a feeder may be definitely positioned, a pair of notched pins carried by said member and arranged with respect to said groove to permit a definite assembling of a feeder and pen, a movable member adapted to be reciprocated over said fixed member, means associated with the last-named member whereby the extent of the insertion of a nozzle over said feeder and pen may be regulated and means to reciprocate said movable member and to return the same to normal position.

3. A tool of the class described including a fixed member having a groove adapted to receive a feeder of a fountain pen, a movable member adapted to hold a pen in position over said feeder and to clamp said pen and feeder together and means adjustably associated with the last-named member whereby the extent of the insertion of a nozzle over said feeder and pen may be regulated.

In testimony whereof I affix my signature.

IGNATZ SALZ.
